UNITED STATES PATENT OFFICE.

EDWARD F. HILL, OF PEEKSKILL, AND WILLIAM HERBERT MYERS, OF BROOKLYN,
NEW YORK, ASSIGNORS TO UNION STOVE WORKS, OF NEW YORK, N. Y., A CORPO-
RATION OF NEW YORK.

STOVE.

1,210,312.

Specification of Letters Patent. Patented Dec. 26, 1916.

Application filed February 23, 1916. Serial No. 80,020.

To all whom it may concern:

Be it known that we, EDWARD F. HILL and WILLIAM HERBERT MYERS, citizens of the United States, residing at Peekskill and 5 Brooklyn, respectively, in the counties of Westchester and Kings, respectively, and State of New York, have invented certain new and useful Improvements in Stoves; and we do hereby declare the following to 10 be a full, clear, and exact description of the invention, such as will enable others skilled in the art to which it appertains to make and use the same.

This invention relates to stoves and has 15 for an object to provide a construction wherein the essential parts thereof may telescope each other to present a compact article for shipment.

An object of this invention is to provide 20 a stove having a firepot provided with a bead about the upper edge thereof, to form annular grooves to receive a shell comprising a combustion chamber either above or below said bead as desired, and to provide a 25 top and bottom member for said stove having provision for reversing said top and bottom members to prepare a compact unit for shipment.

Further objects will be apparent from the 30 following specification, appended claims and drawings, in which,

Figure 1 is a vertical sectional view through a stove constructed in accordance with this invention, showing the same set up 35 for use as a stove, Fig. 2 is a similar view through the parts of the stove showing said parts nested as for shipment, and Fig. 3 is a horizontal sectional view as on the line 3—3 of Fig. 2.

40 Referring to the drawings, 10 indicates the base which may have legs 11 detachably secured thereto, and said base has a depressed central portion 12, over which an upwardly tapering side wall 13 is placed to 45 form an ashpit. The wall 13 is provided with an opening 14 which is normally closed by the door 15 which may be slidably carried by said side wall and this door may be further provided with an opening 16 over which 50 a slide 17 is mounted to regulate the draft for the fire. The wall 13 will be provided with the usual supports for the grate 18 and the upper edge of said wall has an inwardly directed flange 19 to form an annular depression 20 to receive the lower edge of the

firepot 21, which will preferably taper downwardly substantially as shown. This firepot will have a bead 22 about the upper edge thereof, to provide the annular depressions 23 and 24, of which the annular depression 23 receives the lower edge of a side wall 25 which may serve as the combustion chamber and the heater portion of the stove when the stove is set up for use. This portion 25, may be provided with the guides 26 and 27 60 between which the doors 28 are mounted and slide to expose the opening 29 formed in the section 25 for the admission of fuel to the fire. This section 25, is also provided with an opening 30 about which is placed 70 a flange 31 to receive a smoke pipe or the like, and the upper end of this portion 25 is adapted to receive a cover 32 which has the annular beads 33 and 34 formed thereon to form a recessed portion therebetween, in 75 which the upper end of the section 25 rests. The cover 32 may be provided with a removable lid 35 which may also serve for the admission of fuel to the interior of the stove. 80

The foregoing description applies to the stove as set up ready for use as shown in Fig. 1, but when it is desired to crate the stove for shipping, the several parts are rearranged as shown in Fig. 2, in which the annular rib 36 formed on the underface of the bottom 10, engages in the annular depression 23, and one of the ends of the section 25 engages the annular depression 24 to support the firepot 21 as shown inside of the section 25. 85 90

Slight modifications in the construction of the several parts may be made without departing from the spirit of this invention and it is apparent that the several parts need not be assembled in the identical form shown. 95

Having thus described this invention, we claim:—

1. A stove comprising a firepot, ashpit and shell forming a combustion chamber, closures for said combustion chamber and ashpit, said firepot and ashpit being of reduced proportions to telescope in said combustion chamber, and said closures for said combustion chamber and ashpit being interchangeable in altered positions of the parts. 100 105

2. A stove comprising a firepot, and ash pit carried thereby, a shell forming a combustion chamber detachably carried by said firepot, a bead formed on said firepot to re- 110

ceive said shell, and said firepot adapted to be inserted in said shell and suspended by said bead formed thereon.

3. A stove comprising a bottom, a firepot and ashpit, a shell forming a combustion chamber and a top, a bead formed on said firepot to engage one or the other of the ends of said shell, said firepot and ashpit being insertible in said shell, and said top and bottom members being interchangeably carried

by said shell and firepot in the different assembly thereof.

In testimony whereof we affix our signatures in presence of two witnesses.

EDWARD F. HILL.

WILLIAM HERBERT MYERS.
